UNITED STATES PATENT OFFICE

2,212,584

FASTENING-SUPPLYING MECHANISM

Philip E. Burby, Beverly, Mass., assignor to
United Shoe Machinery Corporation, Borough
of Flemington, N. J.

Application October 7, 1939, Serial No. 298,443

11 Claims. (Cl. 1-6)

This invention relates to mechanisms for supplying fastenings to the driving instrumentalities of machines which drive gangs of fastenings, and is herein illustrated as applied to mechanism of the same general character as disclosed in United States Letters Patent No. 1,002,422, granted on September 5, 1911 on an application of R. F. McFeely. Such mechanism comprises a plurality of raceways for fastenings and a separator operated intermittently to separate and deliver fastenings from the raceways. Some machines drive such a large number of fastenings that it is impracticable to provide as many raceways as the number of fastenings driven in each cycle of operations, and they have accordingly been provided with half as many raceways as the number of fastenings driven and with means for operating the separator to deliver two sets of fastenings in each cycle, the first set being delivered to a receiving slide in which the fastenings are retained until the second set is delivered. Such a construction is disclosed, for example, in Letters Patent No. 1,129,882, granted on March 2, 1915 on an application of R. F. McFeely.

It will be evident that if a separator operated twice in each cycle as above described delivers each time the same number of fastenings, an even number of fastenings will be supplied to the driving instrumentalities regardless of the number of the raceways. In some machines, however, it is desirable to drive an odd number of fastenings. The present invention accordingly provides novel means to cause different numbers of fastenings to be delivered respectively by different delivery movements of a separator. For the purpose in view, the construction herein shown comprises a rotatable member associated with one of the raceways and so formed as to prevent delivery of any fastening from that raceway when the member is in one position but to permit such delivery when it is turned to another position, and means movable with the separator for turning the member to different positions so that different numbers of fastenings will be delivered respectively at different times. More particularly, as herein illustrated, the rotatable member consists of a disk having therein diametrically opposite slots each arranged to receive the endmost fastening in the raceway and permit its delivery by the separator when the disk is in the appropriate position and formed between the slots for peripheral engagement with the endmost fastening to prevent its delivery, the disk being turned ninety degrees about its axis

prior to each delivery movement of the reciprocating separator so that different numbers of fastenings are delivered respectively by alternate delivery movements of the separator. For turning the disk there is provided a pawl which is movable with the separator and acts on one of four pins carried by the disk each time the separator moves in one direction, the pawl being yieldable idly upon engagement with another of the pins as the separator receives its delivery movement in the opposite direction. For maintaining the disk in its proper position after each turning movement, there is further provided in the construction shown a spring-controlled member arranged to bear against two of the pins.

The novel features of the invention, including various novel details of construction and combinations of parts, will now be more particularly described with reference to the accompanying drawing and thereafter pointed out in the claims.

In the drawing,

Fig. 1 is a perspective front view of fastening-supplying mechanism constructed in accordance with the present invention, a portion of the structure being broken away;

Fig. 2 is a view substantially in plan of a portion of the structure shown in Fig. 1, the parts being shown in the positions which they occupy after the beginning of a movement of the separator toward the left from its initial position;

Fig. 3 is a view similar to Fig. 2, but showing the parts as they appear after the separator has completed its movement toward the left;

Fig. 4 is substantially a plan view of a portion of the structure, with parts above removed and certain parts in section, illustrating conditions after the separator has moved toward the right to separate and deliver a set of fastenings;

Fig. 5 is a section on the line V—V of Fig. 3; and

Fig. 6 is a plan view of the disk which controls delivery of fastenings from one of the raceways, showing the disk detached from the rest of the mechanism.

Fastening-supplying mechanism of the type illustrated in the above-mentioned Letters Patent, which is constructed particularly for use with tacks, comprises a support 2 or a plurality of inclined raceway devices 4 (hereinafter referred to as raceways) which receive tacks delivered by a hopper (not shown) and support the tacks in rows by their heads. Mounted to reciprocate transversely of the raceways at their lower ends is a separator 6 comprising a plate or series of plates secured to a slide 8. The sepa-

5 rator includes a plurality of pointed fingers 10 the rear edges of which are arranged to engage the shanks of the endmost tacks in the raceways and thus to hold back the rows of tacks, as illustrated in Fig. 2, until the separator has moved far enough toward the left for the points of the fingers to pass beyond the endmost tacks, whereupon the rows of tacks are released and move downwardly along the raceways until the endmost tacks are stopped by engagement with shoulders 12 on the separator, as illustrated in Fig. 3. When the separator is thereafter moved toward the right, the points of the fingers 10 enter between the endmost tacks and the tacks 15 next to them and cause the endmost tacks to move along oblique slots 14 in the separator until holes 16 at the inner ends of the slots align with the heads of the tacks, whereupon the tacks are permitted to drop through grooves 18 formed in a block 20 and through holes 22 in the member 2. The tacks pass from the holes 22, in the construction herein shown, into holes 24 formed in a receiving slide 26 which receives one set of tacks 20 delivered by the separator and retains them until the next set is delivered by the separator, whereupon both sets are delivered from the receiving slide to the tack-driving mechanisms of the machine, in accordance with the disclosure of Letters Patent No. 1,129,882. The block 20, commonly known as the end block, is supported in a readily detachable manner on the member 2 and assists in supporting the separator 6. Fastened to this end block are a plurality of plates 28, herein shown as three in number, which overlap 30 the separator 6 and also overlap the lower end portions of the raceways 4 in recesses in the tops of the raceways, portions of these plates being reduced in thickness and provided with slots 30 (Figs. 2 and 3) in line with the raceway slots to 40 receive the tacks at the lower end portions of the raceways. At the lower ends of the slots 30, except one of the slots as explained below, the plates 28 are provided with holes 32 which permit the tacks to drop as soon as the holes 16 in the 45 separator arrive in alignment with the holes 32. For purposes of this invention there is mounted in a circular recess formed underneath in the middle plate 28 a thin circular disk 34 which lies in the same inclined plane, parallel to the inclination of the raceways, as the slots 30 in the plate, this disk being provided with diametrically opposite slots 36 each arranged to align at times with one of the slots 30, which is shorter than the others, and with the corresponding raceway 4, 50 so as to receive a tack and permit it to be delivered from that raceway by the separator, as illustrated in Fig. 3. At the inner end of each slot 36 is a hole 38 in the disk which permits the tack to drop when the corresponding hole 16 of the separator arrives in alignment therewith, the 55 holes 38 thus serving the same purpose as the holes 32 at the lower ends of the longer slots 30 in the plates 28. When the disk 34 is not in such a position that one or the other of its slots 36 is in alignment with the short slot 30, the periphery of the disk engages the shank of the endmost tack in the corresponding raceway and prevents that tack from moving far enough 60 downwardly to engage the shoulder 12 on the separator and to be separated by the corresponding finger 10 of the separator. By means herein-after described the disk 34 is turned ninety degrees about its axis in a counterclockwise direction, as viewed from above, each time the separator 6 receives its movement toward the left, 65

and the disk remains in the position to which it is thus turned throughout the succeeding tack delivery movement of the separator toward the right. One such movement of the separator toward the left brings one of the slots 36 in the disk 34 into alignment with the short slot 30 in the middle plate 28, as illustrated in Fig. 3, and the next movement of the separator toward the left brings the disk into a position in which that slot 36 is in line with a point on the periphery of the disk midway between the two slots 36 in the disk. It will accordingly be evident that the separator delivers alternately the same number of tacks as the number of the raceways and a number which is one less than the number of the raceways. An odd number of tacks, therefore, is delivered for use in each cycle of operations of the machine.

The disk 34 has an upstanding cylindrical portion 48 extending through a hole in the middle plate 28 and engaged on its upper end by a lug 42 formed on the plate, this lug being provided with a bearing for a stud 44 extending upwardly from the cylindrical portion 48. Projecting downwardly from the lower face of the disk into a recess 46 in the separator 6 are four pins 48 which have enlarged heads thereon below the disk and are shown sectioned in the plane of the lower face of the disk in Fig. 4. Also mounted in the recess 46 in the separator is a pawl 50 controlled by a spring 52 carried by the separator, the spring maintaining the pawl normally in such a position that its end face will engage one of the pins 48 and turn the disk ninety degrees about its axis each time the separator moves toward the left, as illustrated in Figs. 2 and 3. When the separator is next moved toward the right an inclined face 54 on the pawl is engaged by another of the pins 48 to cause the pawl to swing against the resistance of the spring 52 until it passes that pin and is returned by the spring to the position indicated in Fig. 4 adjacent to the pin which it has just passed. In order to insure further that each slot 36 in the disk 34 will align properly with the corresponding slot 30 in the middle plate 28, there is provided a finger 56 having a straight edge arranged to engage two of the pins 48, as illustrated in Fig. 4, to determine the position of the disk after each turning movement thereof. The finger 56 lies in a recess 58 in the end block 20 and is fast on the upper end of a spindle 60 mounted to turn in the block, this spindle being controlled by a spring 62 connected at one end to a pin on the spindle and at the other end to a pin on the block 20. The spring 62 tends to turn the spindle 60 in the direction to force the finger 56 toward the pins 48, and it will be understood that when the disk 34 is turned by the pawl 50 the finger 56 is swung against the resistance of the spring 62 by the action of one of the pins 48 on the finger (Fig. 2), as required to permit the movement of the disk and the pins. It will be evident that near the end of each turning movement of the disk the spring-controlled finger 56 tends, by its engagement with one of the pins, to complete the movement of the disk to the required position. In order to insure that the disk 34 will not catch on the shank of the endmost tack in the corresponding raceway when the disk is turned to carry either of its slots 36 out of alignment with the corresponding slot 30 in the middle plate 28, the disk is provided at one side of each of its slots 36 with a beveled edge 64.

The invention is herein illustrated as applied to mechanism including over the raceways a hinged cover 66 associated with fingers 68 which may, at the will of the operator, be made to enter all the raceways to prevent delivery of tacks therefrom, in accordance with the disclosure of Letters Patent No. 2,047,205, granted on July 14, 1936 on an application of J. C. Jorgensen. The hinged cover 66, which is shown in the upraised position in Fig. 1, is provided with a slot 70 to receive the lug 42 and the upwardly extending cylindrical portion 40 of the disk 34 when the cover occupies its normal position over the raceways.

15 Having described the invention, what I claim as new and desire to secure by Letters Patent of the United States is:

1. In fastening-supplying mechanism, the combination with a plurality of raceways for fastenings, and a device movable intermittently to deliver fastenings from said raceways, of a member mounted for turning movement and associated with one of said raceways for controlling delivery of fastenings from that raceway, said member being so formed as to prevent delivery of any fastening from that raceway when the member is in one position and having a slot arranged to receive a fastening and permit its delivery by said device when the member is turned to another position, and means for turning said member to its different positions in time relation to movements of said device to cause different numbers of fastenings to be delivered respectively by different delivery movements of the device.

2. In fastening-supplying mechanism, the combination with a plurality of raceways for fastenings, and a device movable intermittently to deliver fastenings from said raceways, of a member mounted for turning movement and associated with one of said raceways for controlling delivery of fastenings from that raceway, said member being so formed as to prevent delivery of any fastening from that raceway when the member is in one position and having a slot arranged to receive a fastening and permit its delivery by said device when the member is turned to another position, and mechanism movable with said device for turning said member to its different positions to cause different numbers of fastenings to be delivered respectively by different delivery movements of the device.

3. In fastening-supplying mechanism, the combination with a plurality of raceways for fastenings, and a separator movable intermittently to separate and deliver fastenings from said raceways, of a device mounted for turning movement and associated with one of said raceways for controlling delivery of fastenings from that raceway, said device being arranged to engage the endmost fastening in that raceway and prevent its delivery by the separator when the device is in one position and being so formed as to permit such delivery when it is turned to another position, and means for turning said device to its different positions in time relation to movements of the separator to cause different numbers of fastenings to be delivered respectively by different delivery movements of the separator.

4. In fastening-supplying mechanism, the combination with a plurality of inclined raceways for fastenings, and a separator movable intermittently to separate and deliver fastenings from said raceways, of a disk mounted for turning movement in a plane parallel to the inclina-

tion of the raceways and associated with one of said raceways for controlling delivery of fastenings from that raceway, said disk being arranged for peripheral engagement with the endmost fastening in that raceway to prevent its delivery by the separator when the disk is in one position and having a slot therein to receive the endmost fastening and permit its delivery by the separator when the disk is turned to another position, and means for turning said disk to its different positions in time relation to movements of the separator to cause different numbers of fastenings to be delivered respectively by different delivery movements of the separator.

5. In fastening-supplying mechanism, the combination with a plurality of raceways for fastenings, and a separator movable in one direction to release the fastenings for advancing movements along the raceways and in the opposite direction to separate and deliver the endmost fastenings from the raceways, of a device mounted for turning movement and associated with one of said raceways for controlling delivery of fastenings from that raceway, said device being arranged to engage the endmost fastening in that raceway and prevent its delivery by the separator when the device is in one position and being so formed as to permit such delivery when it is turned to another position, and means movable with the separator for turning said device as the separator moves in the direction to release the fastenings in the raceways to cause different numbers of fastenings to be delivered respectively by different delivery movements of the separator.

6. In fastening-supplying mechanism, the combination with a plurality of raceways for fastenings, and a separator movable intermittently to separate and deliver fastenings from said raceways, of a member mounted for turning movement and associated with one of said raceways for controlling delivery of fastenings from that raceway, said member having therein diametrically opposite slots each arranged to receive the endmost fastening in that raceway and permit its delivery by the separator when the member is in the appropriate position and being formed between said slots for peripheral engagement with the endmost fastening in the raceway to prevent its delivery by the separator, and means for turning said member ninety degrees about its axis prior to each delivery movement of the separator to cause different numbers of fastenings to be delivered respectively by alternate delivery movements of the separator.

7. In fastening-supplying mechanism, the combination with a plurality of raceways for fastenings, and a separator mounted for reciprocatory movements to separate and deliver fastenings from said raceways, of a device mounted for turning movement and associated with one of said raceways for controlling delivery of fastenings from that raceway, said device being arranged to engage the endmost fastening in that raceway and prevent its delivery by the separator when the device is in one position and being so formed as to permit such delivery when it is turned to another position, and a member movable with the separator for engaging a portion of said device to turn the device to a different position each time the separator moves in one direction, said member being yieldable upon engagement with another portion of said device as the separator moves in the opposite direction.

8. In fastening-supplying mechanism, the combination with a plurality of raceways for fastenings, and a separator mounted for reciprocatory movements to separate and deliver fastenings from said raceways, of a device mounted for turning movement and associated with one of said raceways for controlling delivery of fastenings from that raceway, said device being arranged to engage the endmost fastening in that raceway and prevent its delivery by the separator when the device is in one position and being so formed as to permit such delivery when it is turned to another position, a member movable with the separator to turn said device to a different position each time the separator moves in one direction, and spring-controlled means for maintaining the device in the position to which it is thus turned as the separator moves in the opposite direction.
9. In fastening-supplying mechanism, the combination with a plurality of raceways for fastenings, and a separator mounted for reciprocatory movements to separate and deliver fastenings from said raceways, of a device mounted for turning movement and associated with one of said raceways for controlling delivery of fastenings from that raceway, said device being arranged to engage the endmost fastening in that raceway and prevent its delivery by the separator when the device is in one position and being so formed as to permit such delivery when it is turned to another position, a pawl movable with the separator for engaging a portion of said device to turn the device each time the separator moves in one direction, said pawl being yieldable upon engagement with another portion of said device as the separator moves in the opposite direction, and a spring-controlled member for engaging the device to maintain it in the position to which it is thus turned as the separator moves in said opposite direction.
10. In fastening-supplying mechanism, the combination with a plurality of raceways for fastenings, and a separator movable in one direction to release the fastenings for advancing

movements along the raceways and in the opposite direction to separate and deliver the endmost fastenings from the raceways, of a device mounted for turning movement and associated with one of said raceways for controlling delivery of fastenings from that raceway, said device being arranged to engage the endmost fastening in that raceway and prevent its delivery by the separator when the device is in one position and being so formed as to permit such delivery when it is turned to another position, the device being provided with a plurality of projections, and a pawl movable with the separator for engaging one of said projections to turn the device each time the separator moves in the direction to release the fastenings in the raceways, the pawl being yieldable upon engagement with another of said projections as the separator moves in the opposite direction.

11. In fastening-supplying mechanism, the combination with a plurality of raceways for fastenings, and a separator movable in one direction to release the fastenings for advancing movements along the raceways and in the opposite direction to separate and deliver the endmost fastenings from the raceways, of a device mounted for turning movement and associated with one of said raceways for controlling delivery of fastenings from that raceway, said device being arranged to engage the endmost fastening in that raceway and prevent its delivery by the separator when the device is in one position and being so formed as to permit such delivery when it is turned to another position, the device being provided with a plurality of projections, a pawl movable with the separator for engaging one of said projections to turn the device each time the separator moves in the direction to release the fastenings in the raceways, and a spring-controlled member arranged to engage two of said projections to maintain the device in the position to which it is thus turned as the separator moves in the opposite direction.

PHILIP E. BURBY. 45
